UNITED STATES PATENT OFFICE.

LESLIE STEVENS, OF GLEN RIDGE, NEW JERSEY.

APPARATUS FOR SHAPING HAT-CROWNS.

1,316,813.

Specification of Letters Patent. Patented Sept. 23, 1919.

Application filed July 11, 1913. Serial No. 778,420.

To all whom it may concern:

Be it known that I, LESLIE STEVENS, a citizen of the United States, residing at Glen Ridge, in the county of Essex and State of New Jersey, have invented certain new and useful Improvements in Apparatus for Shaping Hat-Crowns, fully described and represented in the following specification and the accompanying drawings, forming a part of the same.

This invention relates to apparatus for shaping hat crowns, and the object of the invention is to provide an improved apparatus of this class whereby the material to be shaped to form the hat crown may be readily pulled to shape and evenly stretched to lie smoothly against the form. The invention has been made more especially with the object of providing an apparatus for shaping hats of woven material such as velvet, plush or satin which can be stretched but little, if any, in the direction of the warp and woof threads thereof, and to provide an apparatus whereby hat crowns of such material may be formed more readily and more perfectly than with apparatus such as has heretofore been used.

In shaping hat crowns, and especially crowns of velvet or other material having a pile or other nap surface, with the aid of heated crown forms and clamping rings which move down over the form to clamp the edge portion of the material against an outwardly extending flange much difficulty and loss has heretofore resulted from the marring of the material forming the lower portions of the crown or the portions adjacent to the clamping flange, and from the difficulty experienced in stretching the material evenly and smoothly over the forms or inability to secure this result to a satisfactory degree. The marring of the material has resulted from the use of a clamping flange at the base of the form of such width that when the material has been stretched over the form and down past said flange and the clamping ring then lowered, the clamping ring strikes the material at a distance more or less, but always consider-

ably, above the line on which the material is clamped when the ring has become seated against the flange. This has necessitated the putting out of imperfect hats or the actual loss of material through the custom of shaping the crown of a depth greater than desired in the finished product and then cutting off the lower or marred portion thereof. The presence of the outwardly projecting flange at the base of the form has also been disadvantageous in that it holds the outer or lower portion of the material away from the heated form, thereby preventing such portion of the material, which is stretched over the form wet, from becoming suitably heated and thereby suitably softened and in condition to be properly stretched smoothly over the whole form. Furthermore, it has been customary to support such crown forms by means of an edge support or standard so formed that it prevents the hands of the operators from entering beneath the edges of the form, with the result that it has been customary to stretch the material about the form by pulling the same straight downward past the clamping flange. When stretched in this way it is very difficult to stretch the material smoothly over the form without wrinkles or puckering. Furthermore, the arrangement of the means for heating the form as heretofore used has not been such as to secure best results.

I have found that in order to secure the most satisfactory results it is desirable that the wet material when placed over and stretched against the form shall lie against or closely adjacent to the form throughout its whole extent so that all that part of the material which is to form the shaped crown shall be quickly heated to the degree necessary to properly soften the material. It may be noted that when the wet material is heated by being placed against the crown form the heated portions first become softened and then begin quickly to set or harden as the moisture is expelled. This setting or hardening of the material under the action of the heated form may begin in as little as

thirty seconds from the time the material is brought into close contact with the form. For this reason it is important that the material shall be quickly and uniformly heated 5 and softened throughout the whole extent of such part as is to form the shaped crown; and I secure this result by substituting for the old projecting flange a narrow clamping shoulder such that the material when 10 pulled down about the form past such clamping shoulder shall lie against or closely adjacent to the shaping surface of the form.

I have discovered, further, that the material may be much more readily stretched 15 about the form without wrinkles or puckering therein if the edge portions of the material are pulled or stretched inward against and about the lower edge of the form than is the case when the material is stretched 20 straight down over the clamping shoulder. I, therefore, support my crown form in such a way as to leave free hand space beneath the lower or base edge of the form, or beyond such edge in the direction of the longitudinal axis of the form, so that the operators may draw the edge portions of the material inward about the lower edge or stretching rim of the form, thereby getting a more ready and better distribution of the 25 strain on the portions of the material to be stretched and more readily holding the material after it has been stretched, or portions thereof while other parts are being stretched, and until the clamping ring is moved into 30 operative position. The invention also includes other features contributing to the successful shaping of hat crowns, all as hereinafter described and specifically pointed out in the claims.

40 A full understanding of the invention can best be given by a detail description of an approved construction embodying the various features of the same, and such a description will now be given in connection with the 45 accompanying drawings; in which—

Figure 1 shows in side elevation and with parts in section such a form of apparatus;

Fig. 2 is a plan view taken on line 2 of Fig. 1 but on an enlarged scale showing the 50 burner for heating the crown form partly in section;

Fig. 3 is a sectional view on line 3 of Fig. 2 of the burner and central tubular standard;

55 As shown in the drawings, the crown form and clamping ring are mounted in a press of well known construction comprising side frames 10 which carry near their upper ends a table or bed 11, and vertical sliding rods 60 12 mounted in bearings in side frames and which carry a cross-head 13 mounted to be vertically adjustable on the rods, as by means of adjusting nuts 14. The rods 12 are normally held in the position shown in

Fig. 1 with the cross-head in its raised position by a spring or springs 15, and are moved downward against the tension of the springs to lower the cross-head by means of a foot treadle 16 which is connected by a link 17 with a lever 18 pivotally mounted 70 on a support 19 and having its free end connected by a link 20 with a cross bar 21 extending between the lower ends of the rods 12. When the treadle has been depressed to give the full downward movement to the 75 cross-head, it may be held by a catch 22 to lock the cross-head against upward movement. The press is also provided as shown with a hand lever 25 by which the rods 12 may be operated to lower the cross-head, but 80 which is especially intended for applying greater power in completing the downward movement of the cross-head after it has been given the greater part of its downward movement by means of the foot lever. This 85 hand lever 25 is fast on a shaft 26 mounted in bearings carried at the ends of the cross bar 21, which shaft 26 carries at each end an arm 27 which is pivotally connected to one end of a link 28 the other end of which is pivoted to one of the side frames. When the hand lever 25 is thrown over to the left from the position shown in Fig. 1, the rods 12 will be drawn downward by the action of the arms 27 and links 28, and similarly if the 90 rods 12 are drawn downward by operation of the treadle 16, the hand lever will be thrown over to the left. When the rods 12 have been given nearly their full downward movement, the arms 27 and links 28 will have 100 been brought into a position in which they stand nearly in line with each other so that a comparatively light force applied to the hand lever 25 will cause a very strong downward pull to be exerted on the cross-head 105 through the rods 12. The construction of the press as above described forms no part of the present invention, and any other suitable press or apparatus for supporting the crown form and clamping ring and causing 110 a suitable approaching movement between the same may be used.

The crown form 30, of suitable material, as metal, and of any desired shape and of hollow construction for lightness and quickness of heating, is mounted on the table or bed plate 11, being supported at a distance above the table and in such a manner as to leave a free space beneath the lower edge or base edge of the form for the hands of the operators in stretching the material on the form. For so supporting the form, it is most advantageously, and as shown, carried by a central support or standard 31 which extends upward from a base plate 32 resting 115 on and secured to the table 11, as by bolts and thumb-nuts extending through slots in the bed in the usual manner for securing

dies, etc., to the table of presses of the kind shown. The form is best removably secured to the standard 31, as by being formed with a central threaded socket as shown to screw 5 on to the threaded end of the standard 31. A crown form may thus be readily removed and a different one placed in its position for use as desired without removing the standard 31.

10 The lower edge portion of the crown form is extended slightly outward to form a narrow clamping shoulder 33 and the part below the clamping shoulder forms a stretching rim 34. The stretching rim is suitably 15 shaped, being best somewhat rounded at its lower outer portion or edge as shown, so that the material may be readily pulled or stretched against and inward about the same.

The clamping ring 40, which is shaped at 20 its lower or operating edge to conform to and coöperate with the clamping shoulder 33 of the form, is hung from the cross-head, as by means of the rods 41 which extend through openings in the arms of the cross-head and are secured thereto by nuts as 25 shown threaded on the rods and whereby the rods may be adjusted up or down to adjust the position of the clamping ring vertically with relation to the cross-head, and, therefore, its position with relation to the crown form when the cross-head has been lowered to operative position.

For heating the crown form, I provide a burner ring 45 which is mounted close up to 30 the bottom of the crown form and has jet openings arranged to direct the flames outward against the lower inner part of the form. As shown, the burner ring is mounted on the standard 31 which is hollow or 40 tubular and provides a mixing chamber with which the burner tube communicates through a tubular arm 46 as shown in Figs. 2 and 3. A mixture of fuel gas and air is supplied to the mixing chamber and thence to the burner 45 tube by means of an injecting tube 47 which may be of any usual or suitable form to cause a suitable proportionate supply of air to be drawn in by a jet of entering gas supplied through the supply tube 48. It will 50 be noticed that the mixing chamber provided by the standard 31 is of comparatively large proportionate size, and I find that with such a comparatively large mixing chamber a much better heating flame is secured than 55 with the burners as ordinarily used not having such large mixing chambers. With the crown form supported with a free open space beneath its lower edge, I am enabled to locate the burner ring close up to the plane of 60 the bottom or base edge of the form, and thus not only secure a better heating of the form but locate the burner where it will not interfere with the hands of the operators in stretching the material over the form. The

clamping ring may be heated in the ordinary 65 manner by a burner tube 50 secured thereto.

The operation of shaping a hat crown with my apparatus will be understood from what has already been stated, but is briefly as follows:—The cross-head being raised, 70 and the crown form being heated to a suitable temperature, the piece of material to be shaped, after having been suitably wet or moistened, is placed over the form and is pulled downward about the form by two operators standing one on each side of the press, each operator grasping the material with his two hands in the usual manner so as to stretch the material over all parts of the form. As the material becomes heated, 75 and thereby softened, it is quickly manipulated and stretched by the operators by being pulled inward against and about the stretching rim of the form to put the material under suitable tension on the form and 80 to stretch out the wrinkles or puckerings which tend to form in the portions of the material covering parts of the sides and lower portions of the form. In so stretching the material, the operators have the advantage of a free space beneath the form in which their hands may work so that with the material stretched over and against the more or less rounded edge of the stretching 85 rim a better distribution of the pull on the 90 material and a better holding of the material when stretched is secured. As soon as the material has been properly stretched over the form, the cross-head is lowered to bring the clamping ring into operative position to 95 clamp the material against the clamping shoulder 33. When the material has dried and set, the cross-head is again raised and the shaped crown lifted off from the form.

It will be observed that the clamping 105 shoulder is made very narrow so that the material when stretched down over the shoulder and about the stretching rim lies against or so closely adjacent to the whole shaping surface of the form that all parts 110 of the material to be shaped against the form will be quickly heated and substantially uniformly softened, thus avoiding the uneven heating and consequent uneven stretching which results, with the old style of crown 115 form having an outwardly projecting base flange, in the initial setting or hardening of a part of the material before the lower or outer portions have become fully softened, or before the stretching action is completed 120 after such softening.

It will be observed, also, that because of the narrowness of the clamping shoulder the clamping ring does not come into contact with the material until just before it reaches 125 its final clamping position, and the wiping by the clamping ring of a considerable portion of the material with consequent marring

of the material which results from the use of the old clamping flange is thus avoided.

What is claimed is:

1. Hat crown shaping apparatus comprising a crown form having a stretching rim against and inward about which the outer portion of the material being shaped may be pulled, means for supporting the form with an unobstructed open hand space beyond the rim in the direction of the longitudinal axis of the form, said space being directly beyond the rim and extending inward from the rim, and means for clamping the material against the form adjacent the stretching rim.

2. Hat crown shaping apparatus comprising a crown form having a stretching rim formed with a rounded edge against and inward about which the outer portion of the material being shaped may be pulled, a central support for supporting the form with an open hand space beyond the rim in the direction of the longitudinal axis of the form, said space being directly beyond the rim and extending inward from the rim, means for heating the form, and means for clamping the material against the form adjacent the stretching rim.

3. Hat crown shaping apparatus comprising a crown form having a stretching rim against and inward about which the outer portion of the material being shaped may be pulled and having a narrow clamping shoulder between the shaping surface of the form and the stretching rim, whereby the material stretched on the form and over the shaping rim will lie against or closely adjacent the whole shaping surface of the form, means for supporting the form with an unobstructed open hand space beyond the stretching rim in the direction of the longitudinal axis of the form, said space being directly beyond the rim and extending inward from the rim, means for heating the form, a clamping ring for coöperating with said clamping shoulder, and means for causing an approaching movement between the form and clamping ring.

4. Hat crown shaping apparatus comprising a crown form having a narrow clamping shoulder adjacent its base edge and a stretching rim beyond the shoulder, a central standard for supporting the form with an open hand space directly beneath the rim and extending inward beneath the body of the form, a clamping ring for coöperating with the clamping shoulder, and means for causing an approaching movement between the clamping ring and the form.

5. Hat crown shaping apparatus comprising a crown form having a narrow clamping shoulder adjacent its base edge and a stretching rim beyond the shoulder, a central standard for supporting the form with an open

hand space directly beneath the stretching rim and extending inward beneath the body of the form, a gas burner supported by said standard in position to heat the form and not to obstruct the hand space beneath the stretching rim, a clamping ring for coöperating with the clamping shoulder, means for heating the clamping ring, and means for causing an approaching movement between the clamping ring and the form.

6. Hat crown shaping apparatus comprising a crown form having a stretching rim against and about which the outer portion of the material being shaped may be pulled, said stretching rim being formed and located with relation to the shaping surface of the form to cause material stretched on the form and inward about the stretching rim to lie against or closely adjacent the whole shaping surface of the form, means for supporting the form arranged to leave an unobstructed open hand space directly beneath the stretching rim and extending inward beneath the body of the form, and means for clamping the material against the form adjacent the stretching rim.

7. Hat crown shaping apparatus comprising a crown form having an open bottom and having a stretching rim against and inward about which the outer portion of the material being shaped may be pulled, a central support for supporting the form arranged to leave an open hand space directly beneath the stretching rim and extending inward beneath the body of the form, a gas burner set up close to the plane of the base of the form for directing the heating flame against the lower inner portion of the form, an injecting tube for supplying a mixture of gas and air, and a mixing chamber of comparatively large capacity between the injecting tube and the burner orifices.

8. Hat crown shaping apparatus comprising a crown form having a stretching rim against and inward about which the outer portion of the material being shaped may be pulled, a central vertical standard for supporting the form with a clear hand space directly beneath the stretching rim, said standard being of hollow tubular form to provide a mixing chamber, a tubular ring burner mounted on said standard close up to the plane of the base edge of the form, said burner tube having burner orifices for directing flame against the lower inner part of the form and communicating through a supply passage with said mixing chamber, and an injecting tube for supplying a mixture of gas and air to the mixing chamber.

9. A hat crown shaping form having a narrow clamping shoulder adjacent its base edge and having its base edge shaped to form a stretching rim against and inward about which the outer portion of the mate-

rial being shaped may be pulled to stretch the material smoothly on the form, and means for supporting the form with an unobstructed open hand space directly beneath the stretching rim and extending inward beneath the body of the form, said shoulder and stretching rim being formed and located with relation to the shaping surface of the form to cause material stretched on the form 10 and about the stretching rim to lie against

or closely adjacent the shaping surface of the form.

In testimony whereof I have hereunto set my hand in the presence of two subscribing witnesses.

LESLIE STEVENS.
